HIDALGO MOYA, OF NORTH EVINGTON, ENGLAND, ASSIGNOR TO IMPERIAL TYPE-WRITER COMPANY LIMITED, OF NORTH EVINGTON, ENGLAND.

TYPE-BAR MECHANISM FOR TYPE-WRITERS.

1,076,602.

Specification of Letters Pat.

Patented Oct. 21, 1913.

Application filed January 30, 1913. Serial No. 745,078.

To all whom it may concern:

Be it known that I, HIDALGO MOYA, a citizen of the United States of America, residing at North Evington, Leicester, England, have invented certain new and useful Improvements in Type-Bar Mechanism for Type-Writers, of which the following is a specification.

This invention is for improvements in or relating to type-bar mechanism for type-writers and has particular reference to type-bar mechanism wherein the type-bars are operated by floating bell-crank levers, that is, levers which are neither definitely pivoted nor definitely guided in fixed guides, but are free to turn and move up and down and are supported in their normal position by the moving parts of the apparatus. Such a type-bar mechanism comprises a type-bar pivoted to the frame of the machine and having a recess on that side remote from the face which carries the type, which recess is situated close to the pivot. The key-lever is of the bell-crank type and has at one end a circular enlargement which fits into this recess, the two parts being kept together by a spring, and the key-lever being further guided by the frame of the machine and by a pivot-pin operating in a slot. The recess is of a comparatively shallow one so that the enlarged end of the key-lever can easily be entered into it without any lateral movement being necessary, so that the two parts are not positively engaged but are kept together by the spring.

The object of the present invention is to so arrange this type of mechanism that the type-bar and key-lever shall at least be positively engaged when the latter is approximately at the end of its down-stroke.

In the accompanying drawings:—Figure 1 shows diagrammatically the form of type-bar mechanism constructed according to the present invention, the parts being in raised position; Fig. 2 shows the parts of Fig. 3 just before the key-lever reaches the end of its down-stroke, and Fig. 3 shows the full striking position with the key-lever at the end of its down-stroke.

Like letters indicate like parts throughout the drawings.

In the old form, the type bar was provided with a recess in which a circular enlarged end of the type bar lever rested. The two parts were kept together by means of a spring and the base of the type bar was so

shaped that it was quite free in all positions of the arm on the key lever, which was employed to operate the universal bar or its equivalent. In the accompanying drawings, 60 I have shown a construction in which the arm E¹ on the key-lever E has the lower part E² on that side which is toward the type-bar, so shaped that its end portion presents a face that corresponds to the arc of a 65 circle struck from the center of the circular enlargement E³ whereby the key-lever is in operative engagement with the type-bar F. The type-bar has in it a recess F¹ to receive the enlargement E³ as before, and the two 70 parts are kept together by a spring G. The type-bar is pivoted to the frame at H and the key-lever is slotted at H¹ to receive a pin H² which is also carried by the frame. The type-bar and key-lever of course are 75 both held in place against lateral displacement by the usual frame members, and it will be observed that the key-lever while it can be depressed bodily, also swings about the pin H² after the manner of a bell-crank 80 lever. This construction, however, forms no part of the present invention which relates entirely to the means for preventing disengagement of the part E³ from the recess F¹. It will be seen that this recess is somewhat 85 shallow so that the parts can be easily assembled without having to introduce one into the other by a lateral movement, and by shaping the face E² in the manner stated and correspondingly shaping the face F² 90 which lies to the back of the recess F¹, the faces E², F² can be made to engage so that displacement from the recess F¹ is impossible after the type-bar has been advanced a given distance.

In Fig. 2 the position is shown in which the faces E², F² come into operative position, and it will be seen that when in this position they both lie sufficiently behind the recess F¹ to positively hold the enlargement 100 E³ in it, and this position is still further insured when the key-lever E is depressed to its full limit as shown in Fig. 5 and the type-bar is striking the platen J.

The action may be more fully described as 105 follows:—The pin H² constitutes a pivot for the key-lever E, which pivot is situated between the key-carrying end and the operative end; this latter may be described as bifurcated, one fork of the bifurcation baying on it the enlargement E³ and lying toward one side of the pivot H, and the other

fork being provided with the curved surface E^2 which co-operates with the correspondingly curved surface F^2 on the heel of the type-bar F and lies toward the other side 5 of the pivot H . The surface E^2 as will be seen faces in the direction in which the key-lever E must be displaced to dislodge the enlargement E^3 from the recess F^1 , so that any tendency to so dislodge the key-lever 10 causes the face E^2 to bear against the face F^2 . The face F^2 , however, cannot be displaced owing to the pivot H being fixed relatively to the frame, so that the face F^2 being in this manner interposed between the 15 recess F^1 and the face E^2 positively locks the key-lever against such displacement as would dislodge the enlargement E^3 from the recess.

It is found that when the type-bar strikes the platen somewhat heavily, and the finger 20 of the operator has been released from the key-lever E , it required a somewhat stiff spring G to prevent the enlargement E^3 from being bounced out of the recess F^1 of the type-bar. This is quite impossible in a 25 construction built in accordance with my invention as the connection between the two parts at the moment of the type-bar striking the platen J is a positive connection and the spring G can therefore be made lighter, 30 so that less force is required to operate the type-bars.

What I claim as my invention and desire to secure by Letters Patent is:—

1. In a typewriter, the combination of a 35 type bar pivoted on the frame of the machine, a floating bell-crank key-lever having at one end a circular enlargement which engages a segmental recess in the type-bar to operate it, a spring connecting the type-bar 40 and key-lever, and means to positively lock the key-lever against displacement in a direction to carry the enlargement out from the recess when the type-bar is nearing the end of its stroke, for the purpose described.

45 2. In a typewriter, the combination of a type-bar pivoted on the frame of the machine, a floating bell-crank key-lever having at one end a circular enlargement which engages a segmental recess in the type bar 50 to operate it, a spring connecting the type bar and key-lever, and guiding means to prevent displacement of the key lever in a direction to carry its enlargement out from the recess in the type bar when the parts 55 are near the position occupied at the end of the stroke and which are so disposed that they only come into operation toward the end of the stroke, for the purpose described.

60 3. In a typewriter, the combination of a type-bar pivoted on the frame of the machine, a floating bell-crank key-lever having at one end a circular enlargement which engages the segmental recess in the type-bar,

a spring connecting the type-bar and key-lever, and an arm on the key-lever having a 65 curved guiding surface facing the direction in which movement of the key-lever would tend to carry its enlargement out from the recess in the type-bar, the curve of this face conforming to part of a circle struck from 70 the center of pivoting of the enlargement, said surface co-operating with a part which lies between it and the recess in the type-bar when the key-lever and the type-bar are 75 in the positions they occupy toward the end of the stroke, for the purpose described.

4. In a typewriter, the combination of a type-bar pivoted on the frame of the machine, a floating bell-crank key-lever having at one end a circular enlargement which engages a segmental recess in the type-bar, a 80 spring connecting the type-bar and key-lever, and an arm on the key-lever having a curved guiding surface facing the direction in which movement of the key-lever would tend to carry its enlargement out from the recess in the type-bar, the curve of this face conforming to part of a circle struck from 85 the center of pivoting of the enlargement, the type-bar having a co-operating surface 90 which lies between the recess and the curved guiding surface of the key-lever arm when the key-lever and type-bar are in the positions they occupy toward the end of the stroke, for the purpose described. 95

5. In a typewriter, the combination of a type-bar pivoted by one end on the frame of the machine, a floating bell-crank key-lever having that end remote from the key bifurcated, one of the forks so provided 100 having at its ends a circular enlargement which engages the segmental recess in the type-bar and lies toward one side of the pivot therefor while the other fork lies toward the opposite side of the pivot, a spring 105 connecting the type-bar and key-lever, the inner face of the key-lever fork which does not carry the circular enlargement being curved to an arc of a circle struck from the center of the enlargement and the type-bar 110 being provided with a heel on the side opposite the recess so placed that as the type-bar nears the end of its stroke the said heel comes into sliding contact with the curved face on the key lever fork and prevents displacement of the key-lever in a direction 115 which would carry the circular enlargement out from the recess, for the purpose described.

In testimony whereof I have signed my 120 name to this specification in the presence of two subscribing witnesses.
